NUMBER PLATE FOR TELEPHONE DIALS

Walter W. Werring, Brooklyn, N. Y., and Trevor S. Huxham, Chatham, N. J., assignors to Bell Telephone Laboratories, Incorporated, New York, N. Y., a corporation of New York

Application January 31, 1934, Serial No. 709,148

5 Claims. (Cl. 40—10.5)

This invention relates to telephone dials and more particularly to the number plates which constitute an essential part thereof.

The telephone dial number plate in common use today consists generally of a metal disc, enameled or otherwise provided with a smooth opaque upper surface upon which are printed or otherwise impressed suitable dial characters. The number plate is located on the dial immediately beneath a rotatable finger wheel provided with a plurality of finger holes through each of which, except the first one, several of the dial characters are visible when the finger wheel is in its normal or unactuated position. Through the agency of the finger wheel, a subscriber may effect the transmission of any series of impulses corresponding to the station designation or telephone number of any other telephone line, by inserting, in the proper sequence, the finger in the finger wheel holes corresponding to the digits comprising the number to be dialed and after each insertion, turning the finger wheel in a clockwise direction to the limit of its rotation, as determined by the position of a finger stop, and then releasing the finger wheel.

It is the object of this invention to provide a new and improved type of number plate for telephone dials which is substantially rigid and in which the exposed surface is improved in its resistance to the yellowing or aging effects of light and to wear.

This object is attained in accordance with a feature of this invention by providing a metal backing or base with a covering of cellulose acetate, which covering will not be affected by light as to cause discoloration and is resistant to wear caused by light and wear.

More specifically, this object is attained by superimposing on and adhesively associating with a metal base plate a series of cellulose acetate films, one of said films providing a contrasting background for printed dial characters and another of said films providing a transparent protective covering for the printed characters, the several films and base plate being united in such a manner as to provide a rigid integral unitary number plate.

The invention will be readily understood from the following detailed description made with reference to the accompanying drawing in which:

Fig. 1 is a plan view of a telephone dial number plate made in accordance with this invention, and

Fig. 2 is an enlarged cross-section of a portion of the number plate shown in Fig. 1 and illus-

trates the relative disposition of the several acetate films which are applied to the metal backing or base.

As illustrated by Fig. 2 the number plate of this invention comprises a metal base plate 11 which is completely enclosed or enveloped in a coating or film 12 of clear cellulose acetate, the upper surface and edges of which are covered by two films 13 and 14 of white cellulose acetate and transparent cellulose acetate respectively, the film 13 being interposed between the films 12 and 14.

The number plate 10 of this invention may be manufactured in accordance with several methods which embody the application of sheet acetate, sprayed acetate lacquer or a combination of both as will now be described.

The metal backing or base 11 may be stamped as an apertured disc or otherwise formed from sheet metal stock and sand blasted to provide it with a rough surface to which the first film or coating of acetate adheres. The disc 11 is then sprayed on both sides and edges with clear cellulose acetate to provide it with the covering film or envelope 12. This coating or film is allowed to dry. A sheet 13 of white acetate is then printed or otherwise provided with the dial characters shown in Fig. 1 and is united with a sheet 14 of clear acetate by hot-pressing or cementing. After a permanent bond has been effected between the sheets or films 13 and 14, the composite sheet so formed is applied to the upper surface or film 12 and hot-pressed or cemented in position. This composite sheet is of suitable dimensions to allow the edges thereof to be formed over the rim or down turned edge of the disc 11. The material formed over the disc edge, as shown in Fig. 2, is hot-pressed to the underside of the disc, the undercoating 12 of clear acetate serving to provide an effective bond therefor.

If desirable, the formed over portions of sheets 12 and 13 may be crimped rather than hot-pressed to the underside of the coated disc.

In accordance with a modified form of the method of manufacture just described, the films 13 and 14 may be applied separately to coated disc 11. The film 13 is applied by spraying white acetate lacquer directly on the acetate coating or film 12 and in such a manner as to cover the disc edges and the underside of the disc rim. This coating is then allowed to dry and the dial characters are printed or otherwise impressed thereon. The clear acetate film 14 may then be applied in sheet form, being hot-pressed or cemented in position and formed over the disc

edges as described in connection with the composite sheet of the previous method. If desirable, the dial characters may be printed on the underside of the clear acetate sheet rather than directly on the white acetate film; in either case the white film constitutes a suitable background for the printed characters. When the dial characters are printed on the underside of the clear acetate sheet, the white acetate may be sprayed directly on the printed surface to form the white background.

The number plate of this invention may also be made by an all-spraying method. This method distinguishes from the method just described only in the substitution of clear acetate lacquer for the clear acetate sheet, the lacquer being applied to the white acetate film by spraying. In this case no forming of material over the disc edges is required. It is essential, of course, that the dial characters be printed on the white acetate film prior to the spraying of the clear acetate finish.

Irrespective of which of the several methods of manufacture just described is resorted to, a dial number plate is produced which comprises a substantially rigid base member completely enveloped in an acetate film, the upper surface of which is adhesively provided with a character bearing film of white acetate which, in turn, is covered with a protective coating of transparent acetate. Number plates constructed in accordance with this invention will not warp nor become discolored due to aging and the effects of light and are very resistant to wear.

What is claimed is:

1. A number plate for telephone dials comprising a rigid plate completely enveloped by a film of cellulose acetate, a character bearing film of cellulose acetate adhesively associated with the enveloping film of acetate and a film or transpar-

ent cellulose acetate adhesively associated with said character bearing film.

2. A number plate for telephone dials comprising a base plate, an envelope of cellulose material in which said base plate is enclosed, a character bearing film of cellulose material and a transparent film of cellulose material covering said character bearing film, said character bearing film, transparent film and envelope being inseparably united one to another and supported by said base plate.

3. A number plate for telephone dials comprising a disc-like base plate having a peripheral lip, an envelope of cellulose material in which said plate is enclosed, a character bearing film of cellulose material and a film of transparent cellulose material, said character bearing and transparent films being united to each other and covering the upper surface and lip portion of said enclosed base plate.

4. The method of manufacturing number plates for telephone dials which comprises enclosing a metal backing or base in an envelope of cellulose acetate, applying to one surface and edges of said envelope a film of white cellulose acetate, printing dial characters on said white film and applying a film of transparent cellulose acetate to said printed film.

5. The method of manufacturing number plates for telephone dials which comprises enveloping a metal backing or base in a film of a cellulose derivative, adhesively covering a portion of the enveloping film with a film of a cellulose derivative, printing dial characters on said second mentioned film and adhesively covering it with a transparent film of a cellulose derivative.
